ELBRIDGE R. HOLMES, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

JACQUARD INDICATOR FOR LOOMS.

Application filed September 4, 1926. Serial No. 133,702.

This invention relates to improvements in jacquard indicators for looms and it is the principal object of the invention to provide improved means for preventing a misindication from the jacquard should the loom be stopped when going either forward or backward with the indication half given.

In my co-pending application Ser. No. 116,750 there is shown a jacquard indicator similar to the one set forth herein but the lever which is connected directly to the jacquard is provided with a series of teeth to cooperate with spring plungers. I find in practice that the plungers, moving in a fixed line, do not afford the adjustment desirable in mechanisms of this kind and furthermore the plungers have to be made in such a way as to prevent rotation on their axes, otherwise when the knife edges pass each other the plunger is likely to turn and interfere with the indication. It is a further object of my invention to provide the lever which is directly connected to the jacquard with an indicating arm movable with respect to the lever and having intersecting inclined faces which define a knife edge to cooperate with a second knife edge adjustable with respect to the lever to afford means for moving the lever properly irrespective of any variations which may be due to workmanship.

The aforesaid application shows a plurality of box controlling units each of which includes a pair of hooks pivotally connected to an oscillatable positioning lever. These hooks are arranged to be engaged by a regularly moving knife which moves in a fixed path and as shown in said application no provision is made to alter the relative positions of the hooks and knife edge. It is a further object of my invention to provide for changing the position of the hooks relatively to the actuator therefor, preferably by making the lugs which cooperate with the jacquard controlled lever movable and adjustable as to position.

With these and other objects in view which will appear as the description proceeds, my invention resides in the combination and ar-

angement of parts hereinafter described and set forth in the claims.

In the accompanying drawings wherein I have shown a convenient embodiment of my invention,

Fig. 1 is a side elevation of a loom having my invention applied thereto,

Fig. 2 is a view similar to a portion of Fig. 1 but on an enlarged scale and showing the indicating mechanism after having been moved to one of its extreme positions by the jacquard,

Fig. 3 is an enlarged horizontal section on line 3—3 of Fig. 2,

Fig. 4 is a fragmentary rear elevation on an enlarged scale taken in the direction of arrow 4, Fig. 2, and

Fig. 5 is a vertical section on line 5—5 of Fig. 4.

Referring more particularly to Fig. 1 it will be seen that I have provided a loomside 10 having vibrator levers 11 pivotally connected with respect to the frame, each lever carrying a vibrator gear 12. Oppositely rotating cylinders 13 and 14 are mounted on the frame and act to rotate the vibrator gears 12 when the latter are properly positioned with respect to the cylinders by pattern mechanism (not shown). Each vibrator lever has a connector 15, attached to a bell crank lever 16 pivoted on a fixed center 17 and having connection with a box lifting lever 18. The lever 18 is connected to box rod 19 for the boxes 20. The vibrator levers 11 will be raised or lowered according to which of the boxes 20 is to become active. The matter thus far described is a well-known form of box motion.

The jacquard indicator mechanism is mounted on a frame 21 and has pivoted thereto an actuator lever 22 provided with a knife or lifter 23 and is connected by means of rod 24 to a cam lever 25. The latter is actuated by a cam 26 secured to the crank shaft 27 of the loom so that for each pick of the loom the knife or lifter 23 will be raised and lowered.

The frame 21 has a forwardly extending arm 28 on which is pivoted as at 29 a series of three-armed positioning levers 30. The op-

positely extending arms of each lever 30 are connected to upwardly extending hooks 31 and the intermediate arm 32 is proportioned to be received by one or another of two cam notches 33 formed in a vibrator controlling lever 34. There is one lever 34 for each of the three-armed levers 30, each of said levers 34 being pivoted as at 35 to the frame 21 and being connected at the other end thereof to a vibrator lifter rod 36 the lower end of which is connected as at 37 to one or another of the vibrators 11. The notches 33 in each of the levers 34 are located at two different levels with respect to the pivot 29 so that as the levers 30 are rocked the lever 34 will be lowered or raised, the lever 34 being in its upper position as shown in Fig. 2 in full lines and being able to move to its lower position when the levers 30 are moved to the dotted line position indicated in said figure.

The hooks 31 are proportioned to be operable one at a time with the knife edge or lifter 23 so that by selecting which of the hooks shall be raised it is possible to rock corresponding levers 30 and therefore the vibrators 11 either to raise or lower the latter and thus alter the position of the active box. The matter described as being mounted on frame 21 and the associated parts may be substantially the same as that shown in patent to Ryon No. 1,554,297.

The mechanism shown in said patent to Ryon is not definite enough in its action in that the controllers for the hooks may stop at an intermediate position so that as the knife 23 moves upwardly both hooks will be indicated thereby, a condition which of course will produce a break. In an effort to overcome this defect I provide a lever 50 for each pair of hooks 31, said lever being pivoted on a stud 51 secured to the frame 21 and having projecting laterally from the lower end thereof three spaced lugs 52 between which extend the upper ends of the hooks 31. Each of said levers 50 is connected by means of upper and lower cords 53 and 54, respectively, to the jacquard mechanism indicated at J in Fig. 1, said mechanism acting to pull on but one cord at a time so that the corresponding lever 50 will be rocked either to the right or left.

Each lever 50 has pivotally connected thereto as at 55 a depending arm 56 provided with a knife edge 57 and there is interposed between each arm 56 and its lever a compression spring 58 serving to push the knife edge 57 away from the lever 50. A laterally projecting arm 59 on the frame 21 is provided with a plurality of slots 60 as indicated in Fig. 4 and each of said slots receives a stud 61 having a knife edge 62. Each stud has a reduced slabbed portion 63 to fit in the associated slot 60 to prevent rotation thereof and each stud is further provided with a screw 64 by means of which it may be held tightly in

position on the arm 59 and also adjusted vertically in the slot 60.

In operation the jacquard mechanism will pull upon one or another of the cords 53 or 54 so that the levers 50 will be rocked either to the right or to the left about the stud 51. When lever 50 moves from the position indicated in full lines in Fig. 2 to that shown in dotted lines the corresponding arm 56 will be moved downwardly so that the knife edge 57 will slide over the upper inclined face of the lug 61 and pass the knife edge 62 of the lug. The pressure of spring 58 will thereafter serve to continue the movement of the lever 50 even though the cord 54 should not receive its full movement due to the stoppage of the loom at an intermediate position or for any other reason. Adjustment of the positions of the lever 50 may be obtained by varying the vertical position of the lug 61, the raising of the lugs carrying the arm 56 upwardly and therefore causing a slight right hand movement of the levers 50 so that the hooks 31 may be positioned with respect to the knife 23.

From the foregoing it will be seen that I have provided a simple and ready means for adjusting the position of the levers 50 and also for insuring proper action between the co-acting knife edges, the lugs 61 being free from the objection previously noted with regard to the plungers heretofore used and the whole arrangement occupying less space than that required in the structure set forth in my pending application.

Having thus described my invention it will be apparent that changes and modifications may be made therein by those skilled in the art without departing from the spirit and scope of the invention, and I do not wish to be limited to the details herein disclosed but what I claim is:

1. In a jacquard indicator for the box motion of a loom, a member connected to and movable by the jacquard mechanism, a regularly moving actuator, a pair of elements operatively connected to the box motion and movable with the member relatively to the path of the actuator, and a pair of cooperating devices acting to complete a motion of the member initiated by the jacquard mechanism, one of said devices being connected to and movable with the member, the other device being capable of assuming any one of a number of fixed positions relatively to the member when the latter is at rest, the variation of the position of said second device rendering possible a variation in the time at which said devices will begin to complete a motion of the member which is initiated by the jacquard mechanism.

2. In a jacquard indicator for the box motion of a loom, a member connected to and movable by the jacquard mechanism, a regularly moving actuator, a pair of elements op-

eratively connected to the box motion and movable with the member relatively to the path of the actuator, and a pair of cooperating devices acting to complete a motion of the 5 member initiated by the jacquard mechanism, one of said devices being connected to and movable with the member, the other device being capable of assuming any one of a number of fixed positions relatively to the member 10 when the latter is at rest, the variation of the position of said second device rendering possible a variation in the time at which said devices will begin to complete a motion of the member which is initiated by the jacquard 15 mechanism, one of said devices being yieldable with respect to the other device.

3. In a jacquard indicator for the box motion of looms, a lever movable under control of the jacquard mechanism, a regularly moving 20 actuator, a pair of hooks operatively positioned with respect to the actuator by the lever, connections between the hooks and the box motion, a pair of members each having a knife edge and co-acting to complete a movement of the lever which is initiated by the jacquard mechanism, one of said members being operatively connected to the lever, and a support for the other member with respect to which said other member may assume any one 25 30 of a plurality of fixed positions, whereby the hooks may be positioned with respect to the actuator by varying the position of said other member.

4. In a jacquard indicator for the box motion of looms, a lever movable under control of the jacquard mechanism, a regularly moving 35 actuator, a pair of hooks operatively positioned with respect to the actuator by the lever, connections between the hooks and the 40 box motion, an element pivoted to the lever and having a knife edge, a second element having a knife edge to cooperate with the knife edge of the first element to complete a motion of the lever initiated by the jacquard 45 mechanism, and means to hold said second named element in any one of a plurality of fixed positions with respect to the first named element, whereby the position of the lever and the hooks may be varied with respect to the 50 actuator by varying the position of the second named element.

5. In a jacquard indicator for the box motion of looms, a lever movable under influence of the jacquard mechanism, a pair of hooks 55 positioned by the lever, a regularly moving actuator, the lever moving the hooks into and out of operative position with respect to the actuator, connections between the hooks and the box motion, and a pair of elements to determine 60 the position of the lever and complete a movement thereof initiated by the jacquard mechanism, one of said elements being operatively connected to the lever, and one of said elements being movable with respect to the axis of the lever, whereby the 65

latter can assume a plurality of positions to vary the position of the hooks relatively to the actuator.

6. In a jacquard indicator for the box motion of looms, a lever movable under influence of the jacquard mechanism, a pair of hooks positioned by the lever, a regularly moving actuator, the lever moving the hooks into and out of operative position with respect to the actuator, connections between the hooks and the box motion, a pair of positioning elements for the lever one of which is relatively fixed and the other of which moves with the lever, and means to vary the normal position of one of the elements with respect to the lever when the latter is in normal position, whereby the position of the hooks may be varied with respect to the actuator.

7. In a jacquard indicator for the box motion of looms, a lever movable under control of the jacquard mechanism, an actuator having a regular movement, a pair of hooks having connection with the lever and being operatively positioned thereby with respect to the actuator, connections between the hooks and the box motion, a member pivotally mounted on the lever and having a knife edge, a second relatively fixed member also having a knife edge defined by inclined surfaces, said knife edges of the members cooperating to complete a motion of the lever initiated by the jacquard mechanism.

8. In a jacquard indicator for the box motion of looms, a lever movable under control of the jacquard mechanism, an actuator having a regular movement, a pair of hooks having connection with the lever and being operatively positioned thereby with respect to the actuator, connections between the hooks and the box motion, a member pivotally mounted on the lever and having a knife edge, a second relatively fixed member also having a knife edge defined by inclined surfaces, said knife edges of the members cooperating to complete a motion of the lever initiated by the jacquard mechanism, one of said members being yieldable.

9. In a jacquard indicator for the box motion of looms, a lever movable under control of the jacquard mechanism, an actuator having a regular movement, a pair of hooks having connection with the lever and being operatively positioned thereby with respect to the actuator, connections between the hooks and the box motion, a member pivotally mounted on the lever and having a knife edge, a second relatively fixed member also having a knife edge defined by inclined surfaces, said knife edges of the members cooperating to complete a motion of the lever initiated by the jacquard mechanism, and means to hold the member pivotally mounted on the lever yieldingly in engagement with the other member.

10. In a jacquard indicator for the box motion

tion of looms, a lever movable under action of the jacquard, a regularly moving actuator, a pair of hooks operatively connected to the lever and positioned thereby with respect to the actuator, connections between the hooks and the box motion, a fixed lug, and an arm pivoted to the lever, said lug and arm having co-acting knife edges, the arm moving about

an axis substantially parallel to the knife edges, and resilient means interposed between the arm and the lever to cause the edges of the lug and arm to co-act to complete a motion of the lever initiated by the jacquard. 10

In testimony whereof I have hereunto affixed my signature.

ELBRIDGE R. HOLMES.
